Attorney.

UNITED STATES PATENT OFFICE.

AUGUST GRÄNTZDÖFFER, OF MAGDEBURG, GERMANY.

VACUUM PAN.

Application filed December 30, 1926, Serial No. 158,029, and in Germany September 18, 1925.

My invention relates to improvements in vacuum pans, and more particularly in vacuum pans used in the manufacture of sugar. The object of the improvements is to provide a vacuum pan in which the flow of the liquid to be heated is improved. With this object in view my invention consists in constructing the heating elements or radiators of the pan so that the heat intensity is increased at these parts of the heating surfaces where the flow of the liquid is directed upwardly, as compared to other parts where the flow is directed downwardly. Thus the upward movement of the liquid is accelerated by increased heating, while the retardation of the liquid flowing downwardly is reduced.

For the purpose of explaining the invention an example embodying the same has been shown in the accompanying drawing in which the same letters of reference have been used in all the views to indicate corresponding parts. In said drawing,

Fig. 1, is a sectional elevation showing a vacuum pan,

Fig. 2, is a sectional elevation showing a radiator element on an enlarged scale,

Fig. 3, is a sectional plan view taken on the line 3—3 of Fig. 2, and

Fig. 4, is a sectional elevation showing a part of a radiator composed of a plurality of radiator elements.

In describing the invention reference will be made to a vacuum pan described in the patent of the United States No. 953,607 granted to me March 29, 1910, which vacuum pan however has been equipped with my improved radiator.

As shown in Fig. 1, the vacuum pan consists of a cylindrical vessel *i* provided with a supply *j* and a discharge *k* for the juice, and with a vapor eduction pipe *l*. The radiator consists of a plurality of annular elements *m* concentrically located one within

the other.

My invention relates more particularly to the construction of the radiator, and in describing the invention I shall at first make reference to the example shown in Figs. 2 and 3. It may be assumed that only a single radiator element such as is shown in Figs. 2 and 3 is used in the vacuum pan, the juice flowing upwardly at the outside of the said element and downwardly at the inner side thereof. As shown the radiator *a* is annular in form. Internally of the radiator

there is a vertical cylindrical partition wall *b* which is fixed to the bottom of the radiator and extends to a point away from the top thereof, thus providing an annular passage *c* through which the outer and inner chambers *e* and *f* of the radiator communicate with each other. The heating medium such as steam is admitted through a pipe *d* to the bottom part of the outer chamber *e*, and the water of condensation is discharged from the bottom part of the inner chamber *f* through a pipe *g*, the pipes *d* and *g* being located at diametrically opposite parts. Thus the heating medium flows upwardly through the outer annular chamber *e*, and downwardly through the inner chamber *f*, and the outer wall of the radiator is intensely heated while the heating of the inner wall is comparatively small. Therefore the flow of the liquid to be heated moving upwardly in contact with the outer wall of the radiator is assisted by the heat transmitted thereto, while the retardation of the flow of the liquid moving downwardly in contact with the inner wall of the radiator is comparatively small by reason of the reduced transmission of heat from the inner wall of the radiator.

Preferably a few openings or drainage ports *o* are provided at the bottom part of the partition *b* to permit the water condensed within the chamber *e* to flow directly to the discharge pipe *g*.

In cases where the liquid flows upwardly through the radiator and downwardly past the outside thereof the heating medium is admitted through the pipe *g*, while the water of condensation is removed through the pipe *d*.

In Fig. 4 I have shown a plurality of concentric annular radiators *a* provided with partitions *b* dividing the radiators into chambers *e* and *f* communicating with each other through annular passages *c*, the construction of the elements being the same as has been described with reference to Figs. 2 and 3. As shown in the said figure, the inlet pipes *d*¹ and the discharge pipes *g*¹ communicate respectively with adjacent chambers of successive radiators, so that in adjacent chambers of successive radiator elements the direction of the flow of the heating medium is the same, the direction of the flow of the heating medium being indicated by arrows *x*. Therefore the upward flow of the liquid between the first and the sec-

2
ond element taken from the right in Fig. 4 is accelerated by the heat transmitted to the liquid from both sides. The flow of the liquid to be heated is indicated by arrows *g*.

5 While in describing the invention reference has been made to particular examples embodying the same I wish it to be understood that my invention is not limited to the form of the radiators shown in the drawing, nor is it limited in other respects except as indicated in the appended claims.

I claim:

15 1. A vacuum pan having therein a hollow annular radiator, a partition extending upward from the bottom of the radiator and dividing it into inner and outer annular chambers, means for admitting a heating medium into one of the annular chambers, a passage at the top of the partition for admitting the heating medium to the other chamber, and a port leading out of the last-named chamber at the bottom of the same.

20 2. A vacuum pan having therein a series of concentric hollow annular radiators, partitions extending upward from the bottom of the radiators and terminating short of the

upper ends of the same to provide annular chambers separated by the partitions whereby a heating medium admitted to one chamber passes over the partition and heats the other chamber to a lesser degree than the first, an inlet port at one side of each partition and an outlet port at the other side, the arrangement of parts being such as to bring two highly heated chambers into juxtaposition between two less highly heated chambers.

3. A vacuum pan having therein a series of concentric hollow annular radiators, partitions extending upward from the bottom of each radiator and dividing it into inner and outer annular chambers, means for admitting a heating medium into one of the annular chambers of each radiator, passages at the upper ends of the partitions for admitting the heating medium to the other chamber, and a port leading out of the last-named chamber at the bottom of the same.

In testimony whereof I have hereunto set my hand.

AUGUST GRÄNTZDÖRFFER.
